TEMPORARY BINDER

Filed March 2, 1934

Patented July 17, 1934

1,967,143

This is a continuation-in-part of application filed January 15, 1934, Serial No. 713,758, now abandoned, and which application relates to a temporary binder of the type disclosed in Letters Patent 1,132,231, dated March 16, 1915, and which application is now abandoned.

UNITED STATES PATENT OFFICE

1,967,143

TEMPORARY BINDER

Charles Caise, Brooklyn, N. Y.
Application March 2, 1934, Serial No. 713,758

5 Claims. (Cl. 129—38)

My invention relates to temporary binders of the type disclosed in Letters Patent 1,132,231, dated March 16, 1915, a type in which a plurality of flat bars are removably held at their ends in brackets.

In binders of the Turner type (Patent No. 1,132,231) in order to place and remove the magazines the flexible strips or bars must be sprung or bowed laterally. This is often a difficult operation, especially when the bars are numerous and located close together. My invention seeks to improve the binder so as to avoid the objection above noted.

A further object of my invention is to construct the brackets and bars so that the bars may be readily snapped into place and removed with little or no lateral bowing or bending thereof.

A further object is to provide a binder whose brackets have provisions to protect the ends of the binder back bar against injury.

Other objects will in part be obvious and in part be pointed out hereinafter.

To the attainment of the aforesaid objects and ends, the invention still further resides in the novel details of construction, combination and arrangement of parts, all of which will be first fully described in the following detailed description and then be particularly pointed out in the appended claims, reference being had to the accompanying drawing, in which:

Figure 1 is a plan view of an open binder equipped with my invention.

Figure 2 is an enlarged section taken longitudinally through the binder back, the central parts being broken away.

Figure 3 is a perspective view of one of the brackets.

In the drawing in which like numbers of reference indicate like parts in all of the figures, 1 represents the covers of the binder and 2 the binder back which may be of the usual construction. Secured by rivets 5, or in any other suitable way, to the back 2 are end brackets each of which comprises a base flange 3, having rivet holes 4, an upwardly inclined wall 6, an inner vertical wall 7, a top wall 8, an outer vertical wall 9 and a bottom flange 10, the flanges 3 and 10 and the wall 8 lying parallel to one another when in normal position. The brackets being made of resilient material can be flexed at the juncture of wall 6 and base 3 so as to be movable to the dotted line position indicated at the right of Figure

2 for the purpose of admitting and releasing the flat bars 12.

The brackets are slotted at 11, the slots extending about half way along the wall 8 from wall 7 and down wall 7 a distance sufficient for the depth of the bars 12 so they may fit in the slots 11 and underlie the unslotted part of the top wall 8 (see Figure 2).

The bars 12 have their ends 13 beveled so that by laying the rods in the slots (see dotted lines, Figure 2) and pressing the same down they will force the brackets to spread apart sufficiently to enable the bar ends to pass into place in the brackets and hold the magazine 15 in the binder.

To release the magazine it is only necessary to press downwardly on the bracket which will cause it to assume the dotted line position at the right of Figure 2 and free the adjacent end of the bar 12 so it may be lifted out with the magazine in which it is located. Pressing down on the magazines at each side of the one to be removed will cause them to press down on wall 6 and thereby move the brackets to the dotted line position to release the bars 12 and enable the selected magazine to be removed. Then on releasing the pressure on the adjacent magazines the brackets will spring back to place and retain the remaining bars.

When the brackets are made to hold a large number of bars 12, the walls 6, 7, 8, 9 and 10 may be slit at intervals as at 14 so that the resilient action is in sections; i. e., only one group of bars need be manipulated to place or remove one.

The flange 10, underlying the back 2, and the wall 9, extending over the end thereof, protect the end of the back from injury. The flange 10 also serves as a stop to limit the spring action of the plate 6.

From the foregoing description, taken in connection with the accompanying drawing, it is thought that the construction, operation and advantages of my invention will be clear to those skilled in the art.

What I claim is:

1. In a binder having covers and a back, brackets secured to said back one at each end of the same, said brackets each including a base plate, an upwardly inclined wall extending from the base plate, an inner vertical wall extending from the inclined wall, an outer vertical wall and a top wall connecting said inner and outer vertical walls, said inner vertical wall and said top wall having vertical slots, and holding bars

having beveled ends located in said slots and underlying the unslotted parts of said top walls, said inclined walls being resilient.

2. In a binder having covers and a back, 5
brackets secured to said back one at each end of the same, said brackets each including a base plate, an upwardly inclined wall extending from the base plate, an inner vertical wall extending from the inclined wall, an outer vertical wall 10 and a top wall connecting said inner and outer vertical walls, said inner vertical wall and said top wall having vertical slots, holding bars having beveled ends located in said slots and underlying the unslotted parts of said top walls, said 15 inclined walls being resilient, said outer vertical walls overlying the edges of said back, and means to limit the upward movement of said brackets under their spring action.

3. In a binder having covers and a back, 20
brackets secured to said back one at each end of the same, said brackets each including a base plate, an upwardly inclined wall extending from the base plate, an inner vertical wall extending from the inclined wall, an outer vertical wall 25 and a top wall connecting said inner and outer vertical walls, said inner vertical wall and said top wall having vertical slots, holding bars having beveled ends located in said slots and underlying the unslotted parts of said top walls, said 30 inclined walls being resilient, said outer vertical walls overlying the edges of said back, and means to limit the upward movement of said brackets under their spring action, said means comprising a bottom wall extending under said 35 back from the lower end of each outer wall.

4. In a binder having covers and a back,

brackets secured to said back one at each end of the same, said brackets each including a base plate, an upwardly inclined wall extending from the base plate, an inner vertical wall extending from the inclined wall, an outer vertical wall and a top wall connecting said inner and outer vertical walls, said inner vertical wall and said top wall having vertical slots, and holding bars having beveled ends located in said slots and underlying the unslotted parts of said top walls, said inclined walls being resilient, said upwardly inclined walls, said vertical walls, said top walls and said bottom walls being slit at intervals to provide a plurality of resilient slotted sections. 80
5. In a binder having covers and a back, 85
brackets secured to said back one at each end of the same, said brackets each including a base plate, an upwardly inclined wall extending from the base plate, an inner vertical wall extending from the inclined wall, an outer vertical wall and a top wall connecting said inner and outer vertical walls, said inner vertical wall and said top wall having vertical slots, holding bars having beveled ends located in said slots and underlying the unslotted parts of said top walls, said 90 inclined walls being resilient, said upwardly inclined walls, said vertical walls, said top walls and said bottom walls being slit at intervals to provide a plurality of resilient slotted sections. 95
5. In a binder having covers and a back, 100
brackets secured to said back one at each end of the same, said brackets each including a base plate, an upwardly inclined wall extending from the base plate, an inner vertical wall extending from the inclined wall, an outer vertical wall and a top wall connecting said inner and outer vertical walls, said inner vertical wall and said top wall having vertical slots, holding bars having beveled ends located in said slots and underlying the unslotted parts of said top walls, said 105 inclined walls being resilient, said upwardly inclined walls, said vertical walls, said top walls and said bottom walls being slit at intervals to provide a plurality of resilient slotted sections. 110

CHARLES CAISE.
